ATTORNEY

UNITED STATES PATENT OFFICE.

BENJAMIN H. SMITH, OF WILKINSBURG, PENNSYLVANIA, ASSIGNEE TO WESTINGHOUSE ELECTRIC & MANUFACTURING COMPANY, A CORPORATION OF PENNSYLVANIA.

THERMAL RELAY.

Application filed February 26, 1921. Serial No. 448,105.

To all whom it may concern:

Be it known that I, BENJAMIN H. SMITH, a citizen of the United States, and a resident of Wilkinsburg, in the county of Allegheny and State of Pennsylvania, have invented a new and useful Improvement in Thermal Relays, of which the following is a specification.

My invention relates to relays and particularly to thermal relays of the cartridge type.

One object of my invention is to provide a thermal relay that shall have sufficient time interval in the operation thereof to effect protection of electrical apparatus from overloads.

Another object of my invention is to provide a thermal relay that shall embody means for reinforcing the same to effectively maintain the co-operating portions of the relay in alignment.

Another object of my invention is to provide a thermal relay in which a time-element shall be obtained in the operation thereof by causing current to traverse a portion of the bimetallic member and permitting another portion thereof to move freely in accordance with the temperature condition thereof developed by the heat conducted thereto from the current-conducting portion.

Another object of my invention is to provide a relay, of the above indicated character, that shall be adapted for use in cartridge-fuse clips and be reliable and effective in its operation.

In practising my invention, I provide a bimetallic member that embodies a relatively wide base portion and a relatively narrow portion that extends therefrom and is free to move. The base portion of the bimetallic member is heated by the current traversing the same, and the narrow portion of the bimetallic member is heated by the heat conducted thereto from the relatively wide base portion.

The narrow portion of the member, when heated to a predetermined degree, is adapted to engage or be disengaged from a stationary contact member, according to the design of relay employed.

The single figure of the accompanying drawings is a diagrammatic view of an electrical circuit and a perspective view,

with parts broken away, of a relay, embodying my invention, that is connected to the circuit.

An electrical translating device 1 is connected to an electrical circuit 2 that is provided with an interrupter 3 for disconnecting the same when the device 1 attains a dangerous temperature. The interrupter 3 is provided with a holding electromagnet 4 and a spring 5 that serves to open the interrupter when the electromagnet becomes de-energized. The energization of the electromagnet 4 is controlled by a thermal relay 6.

The relay 6 comprises, in general, a cylindrical casing 7 of insulating material, two metallic ferrules 8 and 9, blade terminal members 8a and 9a, a tubular metallic conducting member 10, an adjustable contact member 11 and a bimetallic member 12 upon which a contact member 13 is mounted.

The tubular member 10 is slotted, at the one end, to receive the blade 8a and is slotted at the other end to receive a relatively wide base portion 14 of the bimetallic member 12. The base portion 14 of the bimetallic member is secured between the tubular member 10 and the blade 9a to form a substantially rigid structure. A relatively narrow portion 15 of the bimetallic member 12 extends inwardly from the relatively wide base portion 14 within the tubular member 10 to a position at which the contact member 13 is adapted normally to engage the adjustable contact member 11.

The adjustable contact member 11 is mounted on, and supported by but insulated from, the tubular member 10 and extends through an opening in the cylindrical casing 7 that is sufficiently large to preclude any engagement between the contact member 11 and the tubular member. The adjustable member 11 may be so adjusted that the bimetallic member 12 will normally maintain engagement between the contact member 13 and the contact member 11 until a predetermined temperature has been attained by the bimetallic member.

The relay is so connected in the circuit 2 as to be traversed by the current traversing the circuit. The circuit current traverses the blade 9a, the broad base portion 14 of the bimetallic member 12, the tubular conducting member 10, and the blade 8a. Thus, only

the base portion 14 of the bimetallic member is traversed by the circuit current. Heat is conducted from the base portion to the relatively narrow portion 15, causing the same to so expand as to effect the disengagement of the contact member 13 from the contact member 11.

Since the circuit energizing the electromagnet 4 is maintained by the effective engagement between the contact members 11 and 13, the consequent disengagement of those contact members, when the bimetallic member 12 becomes heated to a predetermined degree, de-energizes the electromagnet and permits the spring 5 to open the interrupter.

The disposition of the tubular member 10 around the bimetallic member 12 maintains a dead-air space therearound that prevents convection of heat from that member and serves to so heat lag the bimetallic member that it is caused to have either the same heating characteristic as the device to be protected or to require such time to operate that effective protection of the device 1 may be obtained.

The tubular member 10 serves the double purpose of supporting the bimetallic member 12 and electrically connecting the bimetallic member between the blade members, thus avoiding the necessity of using auxiliary conductors which are usually a source of trouble in devices of this character.

The bimetallic member 12 comprises a plurality of relatively thin bimetallic elements secured together. A bimetallic member so-constructed is more efficient and satisfactory in its operation than a similar member of corresponding size and current-carrying capacity comprising but one relatively thick element, since the tendency for the element to set is obviated.

My invention is not limited to the specific structure that is illustrated, since it may be variously modified within the spirit and scope of the invention, as set forth in the appended claims.

I claim as my invention:—

1. A thermal-responsive device comprising a cylindrical casing, two knife-blade members, a conducting member disposed within the casing and secured to one blade member, and a bimetallic member secured between the conducting member, and the other blade member to form a rigid structure.

2. A thermal relay comprising a cylindrical casing, two knife-blade members, a conducting member disposed within the casing and secured to one blade member, a contact member extending through the casing, and a bimetallic member having a relatively wide portion thereof secured between the conducting member and the other blade

member to form a rigid structure and a relatively narrow portion thereof adapted to be actuated when heated to a predetermined degree to engage the contact member.

3. A thermal relay comprising a cylindrical casing, two knife-blade members, a conducting member disposed within the casing and secured to one blade member at one end thereof and slotted at the other end thereof, a bimetallic member having a relatively wide portion securely disposed between the slotted portions of the conducting member and a relatively narrow portion extending along the conducting member, and a contact member controlled by the narrow portion of the bimetallic member in accordance with the temperature thereof.

4. A thermal relay comprising a cylindrical casing, two knife-blade members therefor, a substantially rigid conducting member connected to one blade member and a bimetallic member connected to the other blade member, the conducting member and the bimetallic member being connected to permit unimpeded movement of a portion of the bimetallic member in accordance with the temperature thereof.

5. A thermal relay for an electric circuit comprising a bimetallic element, one portion of which is traversed by the circuit current and a contact member that is controlled by another portion of the element.

6. A thermal relay for protecting an electrical apparatus comprising a cylindrical metallic conducting member, a bimetallic member having a relatively wide base portion secured to one end of the cylindrical conducting member and a relatively narrow portion extending within the cylindrical member, and a contact member controlled by the narrow portion of the bimetallic member.

7. A thermal relay comprising a metallic conducting member, a bimetallic member, one portion of which is connected in circuit with the metallic member, an enclosing casing and end contact members therefor, one of which is connected to the metallic member and the other of which is connected to the bimetallic member.

8. A thermal relay comprising a conducting member, a bimetallic member having one portion thereof secured to the conducting member and one portion adapted to be actuated when heated to a predetermined degree, a knife-blade member for the conducting member, a knife-blade member for the bimetallic member, a casing for enclosing the whole as a unit and a contact member extending through the casing and adapted to be engaged by the bimetallic member.

9. A thermal relay for an electric circuit comprising a cylindrical casing, two knife-blade members therefor, a conducting member secured to one blade member at one

end thereof, a bimetallic member having one portion thereof securely connected between the other end of the conducting member and the other blade member to be traversed by the circuit current and a second portion free to move in accordance with the heat conducted thereto from the former portion.

10. A thermal-responsive device for an electrical circuit current comprising a bimetallic member having one portion thereof traversed by the circuit and another portion thereof free to move in accordance with the heating developed therein by the heat conducted thereto from the conducting portion thereof.

11. A thermal relay for an electrical circuit comprising a bimetallic member having one portion thereof traversed by the circuit current and another portion thereof free to move in accordance with the heating developed therein by the heat conducted thereto from the conducting portion thereof, and a contact member controlled by the movable portion of the bimetallic member.

12. A thermal relay comprising a cylindrical insulating casing, a cylindrical metallic conducting member extending therein, an adjustable contact member disposed through the casing, a bimetallic member having one

portion thereof secured to one end of the metallic member, and the other end adjacent to and adapted to engage the contact member, a knife-blade member disposed at one end of the casing and secured to the conducting member and a second knife-blade member disposed at the other end of the casing and secured to the bimetallic member.

13. A thermal relay for an electric circuit comprising a bimetallic member having one portion thereof traversed by the circuit current and embodying a relatively large heat-storage capacity and a second portion embodying a relatively small heat-storage capacity and adapted to be heated by conduction from the current-conducting portion.

14. The method of obtaining a time-element in the operation of a bimetallic member which consists in causing current to traverse one portion of the bimetallic member and permitting another portion of the member to move freely in accordance with the heat conducted thereto from the current-conducting portion.

In testimony whereof, I have hereunto subscribed my name this 15th day of February, 1921.

BENJAMIN H. SMITH.
